Specification for Design.

Patented Feb. 14, 1922.

Application filed October 22, 1921. Serial No. 509,736. Term of patent 7 years.

To all whom it may concern:

Be it known that I, SAMUEL H. PAGE, a subject of the King of Great Britain, residing at Stratford, county of Fairfield, State of Connecticut, have invented a new, original, and ornamental Design for Lace, of which the following is a specification, reference being had to the accompanying drawing, forming part thereof.

The figure is a plan view of a piece of lace, showing my new design.

I claim:

The ornamental design for lace, substantially as shown.

In testimony whereof I affix my signature.

SAMUEL H. PAGE.
